FIG. 4

UNITED STATES PATENT OFFICE.

ANGELO ROBERT CLAS, OF SHEBOYGAN FALLS, WISCONSIN, ASSIGNOR TO FALLS MACHINE COMPANY, OF SHEBOYGAN FALLS, WISCONSIN, A CORPORATION OF WISCONSIN.

GLUE-CLAMP.

1,326,186.

Specification of Letters Patent. Patented Dec. 30, 1919.

Application filed June 26, 1916. Serial No. 105,820.

To all whom it may concern:

Be it known that I, ANGELO ROBERT CLAS, a citizen of the United States, and resident of Sheboygan Falls, in the county of Sheboygan and State of Wisconsin, have invented new and useful Improvements in Glue-Clamps, of which the following is a description, reference being had to the accompanying drawings, which are a part of this specification.

This invention relates to glue clamps of the type in which several clamping means are mounted on a common support and are movable to present them successively at a point most convenient for removing the work clamped therein and replacing it with freshly glued work, an opportunity being thus given for the glue to become set during the travel of the work around the machine.

An object of the invention is to provide a glue clamp of this character with power means for moving it step by step with automatic control for bringing the machine to rest after each step of operation thereof.

Another object of the invention is to provide means for supporting the work clamps in the position in which work is removed therefrom and replaced therein, such support being automatically moved out of its operative position on approach of a work clamp and automatically positioned beneath the work clamp at the proper time.

Another object of the invention is to provide for adjustment of the work clamps and to perfect details of construction of the machine generally.

With the above and other objects in view the invention consists in the glue clamp as herein claimed and all equivalents.

Referring to the accompanying drawings, in which like characters of reference indicate the same parts in the different views,

Figure 1 is an end view of a glue clamp constructed in accordance with this invention;

Fig. 2 is a plan view thereof with parts broken away;

Fig. 3 is a front view of the driving end thereof;

Fig. 4 is an end view thereof with parts sectioned on the plane of line 4-4 of Fig. 2; and,

Fig. 5 is a detail view of one of the adjustable clamp hubs.

In these drawings 10 indicates a pair 55 of end frames suitably connected together with bearings 11 formed at their upper ends in which a main shaft 12 is journaled. A keyway extends the full length of the shaft 12, and a number of clamp hubs 13 are slidably fitted on the shaft between the bearings so as to be adjustable and are provided with set-screw-held keys 14 fitting in the keyway of the shaft to lock them in their adjusted positions and to compel them to turn with 60 65 the shaft.

Each clamp hub comprises a disk with a flange projecting at its edge on one face thereof, said flange being notched to receive the ends of the bars of ordinary cabinet 70 maker's clamps 15 which extend radially therefrom, there being screws 16 passing through the ends of the bars and into the intermediate portion of the disk of the clamp hub and a retaining ring 17 clamped 75 to the flange to confine the bars within the notches.

At the driving end of the machine the main shaft 12 extends beyond the bearing and has a gear wheel 18 fixed thereon and 80 meshing with a pinion 19 carried by a countershaft 20 journaled in bearings formed by a bracket 21 which is secured to the end frame. This countershaft 20 carries a fixed pulley 22 and a loose pulley 85 23 arranged side by side and connected by a belt (not shown) with any suitable driving mechanism.

A belt shifter is provided for changing the belt from one pulley to the other, and 90 consists of a sliding rod 24 loosely mounted in the ends of bracket arms 25 which project from the bracket 21. Belt engaging fingers 26 adjustably fixed on the rod 24 are adapted to have the belt pass between 95 them so that they will shift it from one pulley to the other as the rod 24 slides from one position to another. The belt shifter is normally held in the position shown in Figs. 2 and 3, with the belt on the loose pulley, by 100 means of a weight 27 suspended by a cable 28 which is connected to the end of the belt shifter rod 24 after passing around a pulley on the end of a fork 29 projecting from

one of the bracket arms 25. The pull of the weight holding the belt shifter in its normal position may be overcome, however, by a pull on the cable 30 which is connected to 5 the other end of the sliding rod 24, said cable passing around the pulley on the end of a fork 31 projecting from the other bracket arm 24 and then around suitable guide pulleys to a position where it is conveniently 10 accessible to the operator.

Near each end the shaft 12 has fixed on it a cam 32 with hook-shaped cam teeth thereon to engage rollers 33 on the ends of levers 34 which are fulcrumed at 35 to the end 15 frames and have their lower ends connected by links 36 with a U-shaped supporting frame 37 pivotally mounted at its ends to lugs 38 projecting from the end frames. Coil 20 springs 39 connect the supporting frame 37 with the end frames 10 to normally hold the supporting frame in position to have one series of work clamps rest thereon. The 25 action of the cam teeth of cams 32 when the machine has been set in motion by shifting the driving belt to the fixed pulley is to force the rollers out from between the cam teeth from the position shown in full lines in Fig. 4 to the position shown in dotted lines, thereby swinging the levers 34 and 30 moving the supporting frame 37 out of the range of the work clamps. As soon as the shaft has rotated in the direction of the arrow a distance equivalent to one step in the operation of the machine the springs 39 35 return the supporting frame 37 to its operative position, the rollers 33 dropping between the cam teeth again. In this position of the supporting frame 37 the work clamps, which during the turning movement of the shaft were carried past the position of the supporting frame, are adapted to rest thereon while the operator releases the clamps and removes the work and replaces it with freshly glued work. The 40 45 clamps are then tightened again and the machine set in operation by pulling on the cable 30.

The driving connection for the machine is automatically thrown out of operation as 50 soon as the machine has advanced one step. For this purpose the cam 32 at the driving end of the machine is provided with laterally projecting cam teeth 40 which engage with the short end of a lever 41 which is 55 pivotally mounted on the end frame and has a yoke at its longer end engaging a pin through the belt shifting rod 24. Thus at the proper time the belt shifter which is being held on the tight pulley 32 by the operator 60 pulling on the cable 30 is thrown to the loose pulley 23 by one of the cam teeth 40 engaging the lever 41 and swinging it to the position shown in Fig. 3.

With the glue clamp of this invention the

operator may quickly remove the work from 65 the clamps resting on the supporting frame 37 and replace it with freshly glued work, the position of the clamps being such as to facilitate this operation. As soon as the clamping screws have been tightened he 70 pulls upon the cable 30, thereby shifting the belt to the fixed pulley and causing the machine to be set in motion, turning the shaft to lift the work which has just been placed in the clamps and bringing the next row of 75 wood clamps into position. The supporting frame 37 is automatically moved out of the way of the approaching wood clamps and returned to its operative position beneath the latter by the action of the teeth of cam 80 32 against the rollers 33. The operation of the driving mechanism is automatically discontinued by the action of the cam teeth 40 throwing the belt shifter so as to move the belt onto the loose pulley. The operation 85 is repeated and by the time the work has made the complete circuit around the machine it is ready to be removed therefrom, making the operation continuous.

The clamp hubs being adjustable on the 90 shaft adapts the machine for work of various sizes and enables the clamps to be applied at the desired points.

What I claim as new and desire to secure by Letters Patent is:

1. A glue clamp, comprising a suitably supported shaft having a keyway, clamp hubs comprising flanged disks fitting on the shaft and having keys extending into the keyway, means for locking the disks in their 100 adjustments on the shaft, there being notches in the flanges of the disks, wood clamps with their ends fitting in the notches and bolted to the disks, and a retaining ring secured to the flange of the disk to confine 105 the wood clamps in the notches thereof.

2. A glue clamp, comprising end frames, a shaft journaled therein, wood clamps mounted radially on the shaft, cam teeth carried by the shaft, means for turning the 110 shaft, hand operated means for starting the turning means in operation, and a lever adapted to be engaged by the cam teeth for stopping the turning means when the shaft is turned through an angle corresponding 115 with the angle between the wood clamps.

3. A glue clamp, comprising end frames, a shaft journaled therein, wood clamps mounted radially on the shaft, a gear wheel on the shaft, a countershaft having a pinion 120 meshing with the gear wheel, fixed and loose pulleys on the countershaft, a belt shifter, hand controlled means for moving the belt shifter toward the fixed pulley, cam teeth on the shaft, and a lever engaged thereby for 125 moving the belt shifter toward the loose pulley.

4. A glue clamp, comprising end frames,

a shaft journaled therein, wood clamps mounted radially on the shaft, a gear wheel on the shaft, a countershaft having a pinion meshing with the gear wheel, fixed and loose 5 pulleys on the countershaft, a belt shifter, a hand operated cable connected with the belt shifter for moving it toward the fixed pulley, a weight having connection with the belt shifter for moving it

toward the loose pulley, cam teeth on the 10 shaft, and a lever engaged thereby for moving the belt shifter toward the loose pulley.

In testimony whereof I affix my signature in presence of two witnesses.

ANGELO ROBERT CLAS.
